UNITED STATES PATENT OFFICE.

SHEPHERD BROWN SHIPLEY, OF CHATTANOOGA, TENNESSEE, ASSIGNOR OF ONE-HALF
TO ROBERT S. HENRY, OF CHATTANOOGA, TENNESSEE.

DEFLECTOR AND VENTILATOR.

1,082,362.

Specification of Letters Patent. Patented Dec. 23, 1913.

Application filed February 10, 1913. Serial No. 747,502.

To all whom it may concern:

Be it known that I, SHEPHERD B. SHIPLEY, a citizen of the United States, residing at Chattanooga, in the county of Hamilton 5 and State of Tennessee, have invented certain new and useful Improvements in Deflectors and Ventilators; and I do declare the following to be a full, clear, and exact description of the invention, such as will 10 enable others skilled in the art to which it appertains to make and use the same.

This invention relates to that class of dust and cinder guards for railway cars and other windows which are designed to be 15 removably set in position at the edge of the window and project laterally therefrom and which also performs the function of a ventilator.

The object of the invention is to provide 20 a simple and efficient dust and cinder guard so constructed as to operate as a ventilator by causing an outward suction of air from within the vehicle through the window to which it is applied.

25 Another object of the invention is to provide a device of this character which may be readily reversed and used at either side of the window.

With these and other objects in view, the 30 invention consists of certain novel features of construction, and the combination and arrangement of parts as will be more fully described and claimed.

In the accompanying drawings: Figure 1 35 represents a perspective view of a portion of a railway car showing this improved guard applied; Fig. 2 is a similar view of the guard detached; Fig. 3 is a longitudinal vertical section taken on the line 3—3 of Fig. 2; Fig. 4 is a transverse section taken on the line 4—4 of Fig. 2; Fig. 5 is a detail perspective view showing portions of the guard and window frame arranged in juxtaposition ready for connection; Fig. 6 is a 40 plan view of the blank from which the form of guard shown in Figs. 1 to 4 is constructed; Fig. 7 is a perspective view of another form of the invention; Fig. 8 is a transverse section thereof; Fig. 9 is a transverse 45 section of a guard shown composed of wood; Fig. 10 is a diagrammatic view showing the effect of the guard on the air currents whereby it performs its function as a ventilator; Fig. 11 is a view similar to Fig.

4 showing a slightly modified form of the 55 invention.

In the embodiment illustrated a portion of a railway car A is shown having a window B therein which may be of any suitable construction having the usual frame 60 and sashes. The combined guard and ventilator 1 shown in Figs. 1 to 6 is constructed of any suitable material, sheet metal being preferably employed for the main portion or plate 2, which is mounted on a rigid sash 65 support 3 preferably constructed of wood but it may be of any suitable material. This support 3 is preferably beveled in the same direction at its opposite ends to snugly fit within a car window, the sill and the lower 70 edge of the sash of which are usually beveled or inclined, and said support is designed to hold the sash in raised position. This sash support 3 is provided on its opposite side edges with headed studs 4 which 75 are adapted to enter key hole slots 5 formed in plates secured to the window frame (see Fig. 5).

The three walled deflecting plate 2 shown 80 in Figs. 1 to 4 is preferably constructed from a single sheet of bendable material the blank for which is shown in Fig. 6 but it may, if desired, be formed from separate pieces as shown in some of the other figures and as will be hereinafter described. 85

The blank shown in Fig. 6 comprises two plates 6 and 7 connected by a strip 9 at one end, the portion 9 of the strip which is connected with the plate 7 being wider than that connected with the plate 6 and said 90 strip is adapted to be folded on the dotted line 10 during the formation of the guard as will be hereinafter described. The plate 6 is folded longitudinally on the dotted lines 11, 12, 13 and 14 to form the attaching 95 flanges 15 and 16 which extend laterally at the rear edge of the plate and are adapted to be secured by fastening elements to the supporting strip 3, the metal forming these flanges being of double thickness as is shown 100 clearly in Fig. 4. This folding of the plate 6 provides laterally spaced outer walls or plates 17 and 18 between which the plate 7 is designed to extend when the strip 8 has been properly folded to produce the flange 105 19 at the top of the guard, said flange being preferably curved transversely as shown clearly in Fig. 3. Before its insertion be-

tween the plates 17 and 18 the plate 7 is folded on the dotted lines 20, 21 and 22 to form the laterally extending flanges 23 and 24 at the free or outer edge of said plate 7 and which projects beyond the outer edges of the plates 17 and 18 as is shown clearly in Fig. 4. These flanges 23 and 24 also extend laterally on either side of the deflecting plate beyond the outer faces of said plates 17 and 18 for a purpose to be described. The plate 6 is provided between the flanges 15 and 16 with a longitudinally extending groove 25 which is adapted to receive the free edge of the plate 7 when the parts are assembled and as is clearly shown in Fig. 4. The plates 17, 7 and 18 are secured together by fastening bolts on which are mounted between the respective plates spacing sleeves 26 any desired number of which may be employed according to the number of bolts used and which are designed to space the plates the desired distance apart. The plate 7 projects at its upper end and its outer side edge beyond the plates 17 and 18 a sufficient distance to permit the cinders and dust which come in contact with the guard to pass into the space between the outer plate which is arranged toward the front of the car and the plate 7 and through which space they are guided to the lower end of the guard and discharged therefrom in a plane below the car window.

The laterally projecting flanges 23 and 24 at the outer edge of the guard and the flange 19 at the top thereof form important features of this invention and are designed to so direct the currents of air which impinge against the outer face of the deflector as to cause them to circle in the direction shown in Fig. 10 at the rear of said guard thereby forming a circular draft at the rear of the guard opposite the open window which sucks out the air from within the car and serves to thoroughly ventilate the car drawing out the impure air from within. The flange 19 is curved transversely to facilitate the deflection of the cinders away from the car window and prevent their entrance over the top of the deflector or guard. In the use of this improved guard the window sash having been raised a suitable distance to permit the support 3 to be inserted thereunder one of the studs 4 on said support is engaged with the key hole slot 5 in the plate on the window frame whereby said guard is held securely in position with the deflecting or body portion thereof extending laterally at right angles to the side wall of the car as is shown clearly in Fig. 1. When the device is in this position and the train is moving forward in the direction of the arrow *a* the currents of air produced by the onrushing of the train will come in contact with the outer face of the guard 1 and the cinders carried by said currents will be

deflected downwardly, some entering the pockets formed between the plates 17 and 7 in the manner above described and the air coming in contact with the side flange 24 at the front or outer edge of the deflector will be caused to pass rearwardly around said flange and will take the course indicated by the arrows *b* thereby, having a tendency to produce a vacuum decreasing the air pressure at the window immediately behind the deflector. This causes the air in the car to be sucked or pulled out of the windows. This is especially desirable for use on the windows of smoking cars to draw out the smoke from the inside of the car.

In the form shown in Figs. 7 and 8 a single walled guard 1^a is shown somewhat similar to the guard shown in Figs. 1 to 4, being provided with laterally extending flanges 23^a and 24^a at its free side edge and a flange 19^a at its upper edge, said flanges projecting on opposite sides of the plate and being designed to accomplish the function of the same flanges of the other figures, that is, to deflect the cinders and dust downwardly and prevent their entrance into the car window and to cause the currents of air which impinge thereagainst to sweep around the guard and create a suction like draft to draw the impure air from the car. The supporting strip 3^a thereof is designed to fit within the window frame in the same manner as the strip 3 of the other figures and is provided with the same fastening means for securing it within the window.

In Fig. 9 the guard is shown constructed of wood or other similar material and the plate 1^b thereof has a dovetailed connection at its side edges with the supporting strip 3^b and the flange member 23^b but it may be secured thereto in any other suitable or desired manner.

The operation of the forms shown in Figs. 7, 8 and 9 is the same as that of the other figures and therefore need not be again described.

In Fig. 11 of the drawings I have shown the plates 17' and 18' disposed at a slight angle with respect to the central plate 7 so as to increase the space for the cinders and thus increase the draft between the spaced plates.

While I have described my invention with more or less minuteness as regards details and as being embodied in certain precise forms, I do not desire to be limited thereto unduly any more than is pointed out in the claims. On the contrary, I contemplate all proper changes in form, construction and arrangement, the omission of immaterial elements and substitution of equivalents as circumstances may suggest or render expedient.

I claim as my invention:

1. A deflector and ventilator for vehicle

windows comprising a guard composed of laterally spaced plates one of which projects beyond the other at one end and one side and provided with flanges extending laterally on opposite faces of said projecting end and side.

2. A deflector and ventilator for vehicle windows comprising a guard plate struck from a single sheet of bendable material and foldable to form laterally spaced plates one of which is provided at its upper end and outer edge with laterally extending flanges.

3. A deflector and ventilator for vehicle windows comprising a guard plate struck

from a single sheet of bendable material and foldable to form laterally spaced plates one of which is provided at its upper end and outer edge with laterally extending flanges, said flange carrying plate projecting beyond the others and having the flanges secured to the projecting edges thereof.

In testimony whereof I have hereunto set my hand in presence of two subscribing witnesses.

SHEPHERD BROWN SHIPLEY.
